CLAIM

The ornamental design for a manifold device, as shown and described.

DESCRIPTION

FIG. 1 is a front elevation of a manifold for sanitizing soft drink dispensing machines or the like showing my new design;

FIG. 2 is a bottom plan view thereof, the undisclosed top and rear being unornamented;

FIG. 3 is a front elevation of a second embodiment thereof, the undisclosed top and rear being unornamented and the bottom being identical to that shown in FIG. 2.

FIG.1

FIG.2

FIG.3
